[57] CLAIM

The ornamental design for a combined insulated beverage dispenser and tumbler holder, as shown and described.

DESCRIPTION

FIG. 1 is a front elevational view of a combined insulated beverage dispenser and tumbler holder showing my new design;

FIG. 2 is a rear elevational view thereof;

FIG. 3 is a right side elevational view thereof, the left side elevational view being a mirror image thereof;

FIG. 4 is a top plan view thereof; and

FIG. 5 is a top perspective view thereof.

The bottom is substantially plane and unornamented.
